UNITED STATES PATENT OFFICE.

JAMES WILLIAM FULLER, OF ST. PAUL, MINNESOTA.

DESIGN FOR A HANDLE FOR SPOONS, &c.

SPECIFICATION forming part of Design No. 25,169, dated February 18, 1896.

Application filed December 23, 1895. Serial No. 573,157. Term of patent 14 years.

To all whom it may concern:

Be it known that I, JAMES WILLIAM FULLER, a citizen of the United States, residing at St. Paul, Ramsey county, Minnesota, have 5 invented and produced a new and original Design for the Handles of Spoons, Forks, Ladles, and the Like, of which the following is a specification, reference being had to the accompanying drawings, wherein—

10 Figure 1 is an obverse view of the spoon in elevation, showing a fork in dotted lines; and Fig. 2 is a reverse of such spoon, showing a ladle in dotted lines.

15 The same reference-letters apply in both views of the drawings.

Referring to the latter, the handle of the spoon, fork, ladle, or the like is approximately straight and is embossed to represent logs L with the bark thereon and having projecting knots K at certain points. At its upper end this handle diverges in opposite directions (but still maintaining the appearance of logs) and forms a base B upon which rests 20 a log cabin or house. The latter is embossed 25 to represent logs, though on a much smaller scale than those of the handle, and comprises

the house proper, a chimney C, a roof R, and a door D on the obverse side of the design, whereas upon the reverse side the body is embossed to represent a window W in the 30 house proper, the roof R, and the top of the chimney C as rising above the latter, the whole having the appearance of being supported on said base B.

The leading feature of my design consists, 35 therefore, in the handle of a spoon, fork, ladle, or the like whose body portion is formed in the representation of logs terminating at its upper end in a base and supporting thereon a log cabin.

40 What is claimed as new is—

The herein-described design for the handle of a spoon, fork, ladle, or the like, substantially as shown.

In testimony whereof I have hereunto set 45 my hand in presence of two subscribing witnesses.

JAMES WILLIAM FULLER.
